(No Model.)

C. ESPLIN.

NOSE GUARD FOR SAW MILL HEAD BLOCKS.

No. 336,631.

Patented Feb. 23, 1886.

UNITED STATES PATENT OFFICE.

CHARLES ESPLIN, OF MINNEAPOLIS, MINNESOTA.

NOSE-GUARD FOR SAW-MILL HEAD-BLOCKS.

SPECIFICATION forming part of Letters Patent No. 336,631, dated February 23, 1886.

Application filed April 13, 1885. Serial No. 162,058. (No model.)

To all whom it may concern:

Be it known that I, CHARLES ESPLIN, a subject of the Queen of Great Britain and Ireland, (who have declared my intention of becoming 5 a citizen of the United States,) residing at Minneapolis, in the county of Hennepin, in the State of Minnesota, have invented certain new and useful Improvements in Nose-Guards for Saw-Mill Head-Blocks, of which the following 10 specification is a full, clear, and exact description, reference being also had to the accompanying drawings.

In the drawings, Figure 1 is a side view, Fig. 2 is a plan view, and Fig. 3 is a front 15 view, of a head-block base and head-block and a portion of the carriage, showing my improved guards arranged thereon. Fig. 4 is a cross-section of one of the guards on the line $x x$ of Fig. 3.

20 A' A² represent sections of the two main side timbers of the carriage, and B' one of the head-block bases secured across them, as shown.

B² is the adjustable head-block, which is 25 mounted upon and adapted to slide along the base B'.

The head-block and its base, as shown in the drawings, represent one of the many forms in which they are made; but as my invention is applicable to any form of head-block I merely use the form shown to illustrate the invention, and do not wish to be confined to any particular form. In the form shown the "nose" or end a of the base B' 30 toward the saw projects over the side timber, a' , while in other forms the nose may project to a greater or less distance than is hereshown. The carriage, in running back and forth in feeding and receding, travels parallel with the log-platform, and in rolling the logs upon the carriage or in moving them upon the platform one end of a log is sometimes allowed to project over the carriage so that the noses of the head-blocks strike them with great violence, which frequently breaks them or tears 35 them loose from the carriages; and to render such collisions harmless is the object of my invention, which consists in inclined metal guards or shields C C, secured to the carriage 40 on each side of the nose a of the base B', which receive the blow from the log when the

latter is in motion, or strike the log when the carriage is in motion, and cause the log to run up their inclined sides and pass harmlessly over the top of the head-block base B'. It 55 will be observed that the guards C do not touch the base B', but narrow intervals are left between them, as shown at d in Figs. 2 and 3, so that the concussion of the log upon the guards is not imparted to the head-block base; 60 hence no damage can possibly occur thereto so long as the guards are intact.

The guards being formed separately from the head-block bases, if one of them becomes broken, it can be replaced at a small expense, 65 and will not necessitate the replacement of the whole head-block base, as it would if the guards and base were in one piece. By forming the outer sides, e , of the guards inclined the logs will run up over them and the head-block 70 bases without affecting the guards or head-block bases, or straining the bolts which hold them to the carriages. The face of each guard C next to the saw will conform to the general shape of the nose, so as to fully protect it; 75 but at the same time it must not project far enough beyond the nose to interfere with the saw or other parts.

When used in connection with head-blocks in which the noses project to a greater or less 80 distance than shown, the projecting part of the "nose guard" will be made to conform to such projection.

The nose-guards may be formed as a permanent part of the carriage; but I prefer them 85 in the general form shown, as being the most convenient to attach to the carriage, either when first built or as an attachment to carriages already in use.

Having described my invention and set forth 90 its merits, what I claim is—

The guards C C', secured to a saw-mill carriage, and located at the sides of the nose of the head-block, substantially as and for the purpose herein specified.

In testimony whereof I have hereunto set my hand in presence of two subscribing witnesses.

CHARLES ESPLIN.
